[57] CLAIM

The ornamental design for a reveal track, as shown and described.

DESCRIPTION

FIG. 1 is a fragmented top, right hand and front perspective view of a first embodiment of a design for a reveal track; FIG. 2 is a cross sectional view taken along line 2—2 of FIG. 3;

FIG. 3 is a top view of the reveal track of FIG. 1; FIG. 4 is a bottom view of the reveal track of FIG. 1; FIG. 5 is a front view of the reveal track of FIG. 1; FIG. 6 is a cross sectional view taken along line 6—6 of FIG. 7;

FIG. 7 is a left hand side view of the reveal track of FIG. 1; FIG. 8 is a right hand side view of the reveal track of FIG. 1;

FIG. 9 is a fragmented perspective view of a reveal track according to a second embodiment of the present invention; FIG. 10 is a cross sectional view taken along line 10—10 of FIG. 11; and,

FIG. 11 is a front view of the reveal track of FIG. 9 with the rear view being identical in appearance.
